UNITED STATES PATENT OFFICE

1,995,423

ADJUSTABLE DRESS

Irving Greenberg, Brooklyn, N. Y.

Application February 26, 1934, Serial No. 713,032

2 Claims. (Cl. 2—76)

My invention relates to women's dresses and particularly to those that are manufactured in quantities and sold to the trade as finished, ready to wear dresses.

5 The object of this invention is to improve the method of cutting and manufacturing dresses for women so as to eliminate costly alterations at the place of retailing the dresses, and to furnish the buyer of a ready made dress a better fitting garment than has been possible heretofore.

At the factory, dresses for women are cut according to standardized measurements for each size and fitted on dummy figures or model forms.

10 In the making of the patterns and the cutting of the dresses, approximately a half inch of additional material is allowed for seams on all sides where the garment is to be stitched.

15 On one side of the dress, usually the left side of the wearer, an opening of about seven or eight inches is left which is finished with a narrow strip of material stitched on both sides of the opening on which the separable fasteners are sewn on.

20 A dress that fits the factory model form is considered a good fitting dress and ready for the market.

25 However, nature has not created woman according to the standard proportions of the factory model forms and while all the women in a given group might have 39 inch hips and buy size 16 dresses, other measurements of their bodies may vary.

30 The hips may be higher, or the waist line may vary from one to one and one-half inch smaller or larger than the standard measurements used 35 in the cutting of the dress at the factory.

35 This condition has brought about the specialization of certain types of measurements, by some manufacturers, under different classifications such as "Misses", "Juniors", "Half or Little 40 Women's" and "Women's" sizes.

Therefore, a woman accustomed to wear a size 18 ready made dress in "Misses" sizes, can also wear, with slight alterations, a size 36 in "Women's" sizes, or a size 17 in "Juniors" sizes, 45 or a size 18½ in "Half or Little Women's" sizes, providing that she likes the design of the particular dress.

50 But since the same design is not made in all the different size classifications, most manufacturers specializing in only one classification, one can readily see the great number of cases requiring alterations to make such dresses wearable.

55 As dresses are cut and made at the present time with no provisions for ready adjustments, costly alterations are necessary in most cases, or

the woman has to wear an imperfectly or ill fitting dress.

In my invention I provide means for the ready adjustment about the waist line of a dress to secure perfect fitting without alterations as hereinafter fully described, illustrated in the accompanying drawing and set forth in the claims. 5

In the drawing:

Figure 1 illustrates a perspective view of a dress as worn by a woman and embodying my 10 invention.

Figure 2 is a side view of a dummy figure upon which has been assembled the front and back "foundation" patterns of a dress embodying my 15 invention.

Figure 3 shows the "foundation" pattern embodying my invention, which is used for cutting the back portion of a dress and with modifications for cutting the front part of the dress.

Figure 4 is a pattern of a reinforcing piece attached to the extension of the "foundation" pattern. 20

Figure 5 is an enlarged cross sectional view through one side of the waist and reinforcing member. 25

Figure 6 is an illustration of the various forms that may be given to the projection or extension of the main pattern and to the reinforcing piece.

In general dress manufacturing, the front and the back of a dress, regardless of the number of 30 pieces used or the form given to individual decorative cuts and stitchings, are basically of an outline as shown by the "foundation" pattern in Figure 3 with only slight differences between the front and back outlines. 35

The edges of the back and front are stitched together along the lines 11 forming the sides and along the lines 12 forming the shoulders of the dress.

The front pattern is modified as shown by the 40 dash lines 14 and 16 of Figure 3, the line 16 being often given various forms to suit the wishes of the designer.

The sleeves are stitched to the dress along the lines 13 and 14 and the neck line is trimmed or 45 finished along the lines 15 and 16.

The dress thus assembled can be slipped over the head of the wearer but since the bust measurements and the hip measurements are generally greater than the waist line measurements, 50 an opening 17 must be left intermediate the bust and hip lines to facilitate dressing.

In the present dressmaking art, as heretofore noted, this opening 17 is edged with a narrow piece of material stitched to both the back and 55

front part of the dress, turned in and provided with separable fasteners to close the opening.

During the manufacturing process of a given size this dress is fitted on a standard dummy figure shown in Figure 2 having an approximate front profile 18 and back profile 19.

It can readily be seen that a dress fitting perfectly on a dummy figure will not fit a wearer when the bust dimension is larger as at 20 or smaller as at 21 or if the hip dimension is larger as at 22 or smaller as at 23.

A smaller bust or hip measurement will result in a loose, flabby fitting and a larger bust or hip measurement will result in a tight, stretched fitting, both exceptions necessitating extensive alterations of the dress about the waist line to produce a perfect fit.

With my invention I avoid these alterations which are costly, and I obtain a better fitting garment and I make it possible to either reduce, modify or eliminate the specialization of certain types of measurements now necessary and further make it possible for the retailer to carry in stock a larger variety of designs with a smaller variety of specialized sizes of dresses.

To that end I provide an extension 25 from the side 11 of the foundation pattern, the form of which may be varied from that shown, by the requirements of the dress design or the wishes of the manufacturer as illustrated at 26 and 27 and 28 in Figure 6.

Regardless of the form taken by the extension 25, the basic side line of the foundation pattern remains on line 11.

It is therefore obvious that this extension 25 may be attached to the foundation pattern by stitching along line 11, or it may be provided along both sides of the pattern, or it may be placed on the right side instead of the left side of the pattern, or it may be attached to front foundation pattern as required by the particular design of the dress or the wishes of the manufacturer, although I prefer to have this extension 25 of one piece with the back foundation pattern and to place it on the left side of the back of the dress of the wearer.

The slot or opening 17 and the extension 25 is made to extend from the bust to the hip lines, and is reinforced by the piece 29 shown in Figure 4.

To the edge 30 of the extension 25 I secure by stitching the edge 31 of the reinforcing piece 29, after which this reinforcing piece is turned under and restitched to form a neat smooth edging as shown by the section in Figure 5.

The front edge 32, forming the side of the opening 17 opposite to that formed by the extension 25, is trimmed with a narrow piece of material in accordance with present practice.

When a garment is manufactured as described herein the extension piece 25 projects under the edge 32 forming the opposite side of opening 17 and thereby prevents the exposure of undergarments.

The covering of undergarments at the opening 17 is only a secondary purpose of this invention, the main purpose being to provide a sufficiently

large opening and sufficient extended material on one side of the opening to permit and facilitate the perfect fitting of a garment without any alterations other than the sewing on of the separable fasteners.

Therefore, when a garment embodying my invention is manufactured to fit the standard size shown by the profiles 18 and 19 of the dummy figure in Figure 2, it can be readily adjusted to a person with the large bust measurement 20 by 10 securing the separable fasteners to the extension 25 along the line 40.

Similarly when the bust measurement is small as at 21 fasteners will follow the line 41 and when the hip measurement is large as at 22 the fasteners will follow the line 42 and when the hip measurements are small as at 23 the fasteners will follow the line 43.

The curvatures of the lines 40 to 43 incl. are exaggerated for purposes of illustration while in reality these curvatures are hardly noticeable.

It is obvious that under all these conditions and variations and others too many to describe herein, the garment can be adjusted to obtain a perfect fit upon the wearer by simply securing one 25 part of the separable fastener to the narrow edging 32 on one side of the opening 17 and securing the other part of the fastener to the reinforced extension piece 25 at such points as dictated by the needs of the fitting, having at all 30 times sufficient material to take up these contour variations and also to conceal the undergarments along the opening 17.

Having thus described my invention what I claim and desire to secure by Letters Patent is: 35

1. A dress comprising a waist portion, a skirt portion integral therewith, said dress having an opening in a side seam, said opening extending longitudinally and intermediate the bust and hip lines only, one of the edges of said opening 40 being finished and the other provided with an extension, said extension to be normally positioned beneath and overlapped by the finished edge of the opening, means on the finished edge cooperating with means on the extension to form separable fasteners whereby the opening is closed, the means on the extension being secured at predetermined positions whereby the closure is made along a line dictated by the profile of the wearer to obtain a perfect fitting dress.

2. A dress comprising a waist portion, a skirt portion integral therewith, said dress having an opening in a side seam, said opening extending longitudinally and intermediate the bust and hip lines only, one of the edges of said opening being finished and the other provided with an extension, a reinforcement on said extension, said extension to be normally positioned beneath and overlapped by the finished edge of the opening, means on the finished edge cooperating with means on the extension to form separable fasteners whereby the opening is closed, the means on the extension being secured at predetermined positions whereby the closure is made along a line dictated by the profile of the wearer to obtain a perfect fitting dress.

IRVING GREENBERG.
